Specification for Design.

Patented June 24, 1913.

Application filed February 29, 1912. Serial No. 680,738. Term of patent 14 years.

To all whom it may concern:

Be it known that I, JOHN M. ADAMS, a citizen of the United States, and a resident of Chicago, in the county of Cook and State of Illinois, have invented a new, original, and ornamental Design for a Corner Member for a Bed-Spring Frame, of which the following is a specification, reference being had to the accompanying drawing, forming part thereof.

The figure is a perspective view of a corner member for a bed spring frame embodying my design.

I claim:

The ornamental design for a corner member for a bed spring frame, as shown.

JOHN M. ADAMS.
